UNITED STATES PATENT OFFICE

142,169

DESIGN FOR A SCARF OR SIMILAR ARTICLE

Selma Levy Hermanos, New York, N. Y.

Application May 30, 1945, Serial No. 119,812

Term of patent 3½ years

(Cl. D3—12)

To all whom it may concern:

Be it known that I, Selma Levy Hermanos, a citizen of the United States of America, residing in New York, county of New York, and State of New York, have invented a new, original, and ornamental Design for a Scarf or Similar Article, of which the following is a specification, reference being had to the accompanying drawing, forming part thereof.

The figure on the drawing is a plan view of a scarf or similar article showing my new design.

I claim:

The ornamental design for a scarf or similar article, substantially as shown.

SELMA LEVY HERMANOS.
